INTERNAL COMBUSTION ENGINE

John F. Hermann, Havana, Ill.

Application February 17, 1931. Serial No. 516,421

4 Claims. (Cl. 123—50)

This invention relates to certain new and useful improvements in internal combustion engines, and has more particular reference to an internal combustion engine of the valveless supercharged type.

The principal object of this invention is to provide an engine of such construction as to preclude the use of valves by superior means of admission and exhaust for each cylinder.

10 A still further object of the invention is to provide a novel self contained supercharging device.

15 A still further important object of the invention is to provide a novel means for obtaining positive intake and exhaust port openings and closing at a predetermined point in the cycle of operation.

20 A still further important object of the invention is to provide a novel means of obtaining large cubic displacement and long expansion strokes and very narrow limits of its working members.

25 Other objects and advantages of the invention will become apparent during a study of the following description, taken in connection with the accompanying drawings wherein:

Figure 1 is a vertical transverse sectional view taken through the improved engine.

Figure 2 is a transverse sectional view taken 30 substantially on the line 2—2 of Figure 1.

Figure 3 is a similar view taken substantially on the line 3—3 of Figure 1.

Figure 4 is a transverse sectional view taken substantially on the line 4—4 of Figure 1.

35 Figure 5 is a vertical sectional view taken substantially on the line 5—5 of Figure 1.

Referring more in detail to the drawings, it will be seen that the hinged block includes a crank case 1 having a cylinder 2 of relatively large diameter integral therewith and rising vertically therefrom. A cylinder 3 of relatively small diameter rises vertically from the top of cylinder 2 and is arranged concentrically thereof.

40 Mounted for reciprocation in cylinder 2 is what may be termed a "charging" piston 4. A pair of oppositely disposed relatively short connecting rods 5 are connected at their upper ends as at 6 to the piston 4. At their lower ends the connecting rods 5 are oppositely connected as at 7 to cranks 8 of a crank shaft 9 journalled in the crank casing 1. The ends of crank shaft 9 are journalled in oppositely disposed alined bearings 10, and on one end thereof said crank shaft is provided with a fly wheel 11.

45 Piston 4 has integrally therewith and oper-

able within cylinder a relatively elongated extension 12 capable of reciprocatory movement in the cylinder 3.

The cylinder extension 12 adjacent the lower end thereof is provided with an annular series of 60 circumferentially spaced lateral exhaust ports 13 adapted to register with an annular exhaust passage 14 provided in the lower portion of the cylinder 3. Exhaust passage 14 has a lateral exhaust outlet 15.

65 The reduced extension 12 is divided into a relatively shallow upper compartment 16, adapted to contain a cooling medium, and at its upper end provided with a circular series of relatively spaced ports 25 to form a "fluid break" for the 70 cooling medium and a relatively deep lower compartment 17 through the medium of a partition or head plate 18. Directly below the partition plate 18 there is provided for the compartment 17, a plurality of circumferentially spaced intake 75 openings 19 adapted to register with a fuel intake annular passage 20 when the exhaust ports 13 are in registry with the exhaust passage 14. Annular intake passage 20 is provided in cylinder 3 adjacent the upper end of the cylinder 3 and is 80 provided with a lateral intake 21.

85 Intake 21 is connected with the intake 22 of cylinder 4 through the medium of an intake manifold pipe 23 that adjacent its upper end is provided with a lateral intake 24 adapted to be 85 coupled to a fuel supply pipe leading from a carburetor or other suitable source of supply (not shown). As shown in Figure 1 any suitable means, such as the valve device 35 is interposed between the intake 24 and the aforementioned 90 supply pipe of the carburetor for the purpose of preventing the escape of the compressed fuel on the compression stroke of the engine.

Piston 4 is provided with an axial opening in 95 registry with cylinder 12 for accommodating power piston 26, which piston is also capable of reciprocatory movement in chamber 17 of cylinder 12.

A relatively elongated connecting rod 27 is operatively connected with power piston 26 through 100 the medium of a suitable wrist pin 28 journalled in the piston 26. At its lower end connecting rod 27 is operatively connected as at 29 with an intermediate crank 30.

105 For closing the upper end of cylinder 3 is a closure plate 31 bolted to a flange provided at the upper end of said cylinder as at 32.

Cylinder 3 adjacent its lower end and above exhaust passage 14 is provided with a lateral 110

spark plug hole 33 for accommodating a conventional type of spark plug 34.

Outer cranks 8 have a lesser crank radius than the center crank 30 so that during operation of the internal combustion engine, cylinder 12 and power piston 26 will move relative to each other at different rates of speed until their respective cranks are one hundred and eight degrees opposite from the position of the respective cranks 10 when the fuel charge has been compressed to the maximum, which is when one of the series of ports 19 is in registry with the spark plug hole 33 for igniting the compressed fuel charge.

At the completion of the power stroke the parts 15 are in the position shown in Figure 1. Assuming that the engine has just fired resulting in the completion of the power stroke, it will be apparent that the rotating crank shaft 9 will cause piston 26 to move upwardly on its compression stroke and piston 4 to move downwardly causing cylinder 12 to move in a like direction relative to piston 26. Piston 4 thus moving downwardly will cause suction for drawing a fuel charge from the source of supply into manifold or feed pipe 23. During this relative movement 20 of pistons 26 and 4 it will be apparent that due to the difference in the radius or throw of cranks 8 and 30 piston 26 will move at a greater rate of speed than cylinder 12 which action results 25 in the positioning of piston 26 opposite the ports 13 for closing the latter prior to the moving of ports 19 downwardly and out of registry with the intake passage 20. Ports being thus closed, and communication between chamber 17 and passage 30 being still established will permit of the chamber 17 being charged with fuel under pressure. This feeding of the charge to chamber 17 under pressure will take place subsequent to the 35 igniting of the compressed fuel in chamber 17 and during the power stroke of piston 26 as 40 will be hereinafter made more apparent.

Manifestly, during the compression stroke, the fuel admitted into chamber 17 will be compressed between the top of piston 26 and the partition or head plate 18 to its maximum degree 45 when ports 19 are in registry with the spark plug hole 33, at which time the compressed fuel will be ignited. Expansion of the gases following the combustion will of course force piston 4 downwardly on its power stroke, and force cylinder 12 upwardly within cylinder 3. Piston 4 50 will also move upwardly forcing the fuel previously drawn into the manifold pipe 23, from the pipe 23 through the intake passage 20 to finally be forced under pressure into chamber 17 55 when ports 19 have been moved into registry with the passage 20, which will of course take place when cylinder 12 is at the limit of its up stroke. The registry of ports 19 with passage 60 20 will of course be subsequent to the movement of piston 26 downwardly below the ports 13, so that the charge of fuel under pressure into chamber 17 will be also utilized for scavenging chamber 17, the products of combustion being forced through the ports 13 when piston 26 has reached 65 the limit of its downward or power stroke.

The products of combustion thus passing through the ports 13 will discharge from the exhaust passage 14 through the exhaust port 70 15 of the passage.

Referring again to the chamber 16 and ports 25 it is to be understood that the chamber 16 will be substantially half-filled with oil, and upon reciprocation of the cylinder 12 the oil 75 will be subjected to a high state of turbulence

providing for efficient cooling of the combustion chamber in the cylinder 12.

As is well known, as the heat of the partition forming the bottom of the chamber 16 is absorbed by the oil, the lighter ends of the oil will vaporize, and the oil accumulating on the walls of the cylinder 3 will be scraped therefrom by the upper edge of the wall of the chamber 16 as the cylinder 12 moves upwardly, the oil being thus scraped off the wall of the cylinder 3 being directed into, or returned to the chamber 16. In this manner "a fluid brake" is provided since through the medium of the ports 25 there is caused an immediate drop from a pressure on the upper edge of the chamber 16 to zero pressure, it being apparent that the edges of the walls of the chamber 16 about the openings 25 also serve to scrape the oil from the walls of the cylinder 3, and the oil being thus scraped from the walls of the cylinder 3 is directed through the ports into the chamber 16 thus preventing loss of oil by precluding the passage of oil past the piston sleeve 12.

Even though I have herein shown and described the preferred embodiment of the invention, it is to be understood that the same is susceptible of changes, modifications and improvements coming within the scope of the appended claims.

Having thus described my invention, what I claim as new is:

1. An internal combustion engine comprising in combination a cylinder of relatively large diameter, a second cylinder of relatively small diameter integral with the first mentioned cylinder and connected therewith concentrically of the first mentioned cylinder, a piston mounted for reciprocation in the first mentioned cylinder and having a cylinder extension capable of reciprocatory movement in the second mentioned cylinder, a closure head for said cylinder extension adjacent the free end of the latter, said second cylinder adjacent one end thereof provided with an annular fuel intake passage and adjacent the other end thereof provided with an annular exhaust passage, each of said passages provided with a lateral port, said cylinder extension adjacent said closure end provided with a series of circumferentially spaced intake ports adapted to register with said intake passage, said cylinder extension being provided remote from said closure head with a series of circumferentially spaced exhaust ports adapted to register with said exhaust passage, a piston mounted for reciprocation within said cylindrical extension, a crank shaft, a relatively elongated connecting rod operatively connecting said second piston with one crank of said crank shaft, relatively shorter connecting rods operatively connecting the first mentioned piston with other cranks of said crank shaft.

2. An internal combustion engine comprising in combination a cylinder of relatively large diameter, a second cylinder of relatively small diameter integral with the first mentioned cylinder and connected therewith concentrically of the first mentioned cylinder, a piston mounted for reciprocation in the first mentioned cylinder and having a cylinder extension capable of reciprocatory movement in the second mentioned cylinder, a closure head for said cylinder extension adjacent the free end of the latter, said second cylinder adjacent one end thereof provided with an annular fuel intake passage and adjacent the other end thereof provided with an annular ex-

haust passage, each of said passages provided with a lateral port, said cylinder extension adjacent said closure end provided with a series of circumferentially spaced intake ports adapted to register with said intake passage, said cylinder extension being provided remote from said closure head with a series of circumferentially spaced exhaust ports adapted to register with said exhaust passage, a piston mounted for reciprocation within said cylindrical extension, a crank shaft, a relatively elongated connecting rod operatively connecting said second piston with one crank of said crank shaft, relatively shorter connecting rods operatively connecting the first mentioned piston with other cranks of said crank shaft, and an intake manifold connecting the first mentioned cylinder with the port of said intake passage. 80

10 3. An internal combustion engine comprising in combination a cylinder of relatively large diameter, a second cylinder of relatively small diameter integral with the first mentioned cylinder and connected therewith concentrically of the first mentioned cylinder, a piston mounted for reciprocation in the first mentioned cylinder and having a cylinder extension capable of reciprocatory movement in the second mentioned cylinder, a closure head for said cylinder extension adjacent the free end of the latter, said second cylinder adjacent one end thereof provided with an annular fuel intake passage and adjacent the other end thereof provided with an annular exhaust passage, each of said passages provided with a lateral port, said cylinder extension adjacent said closure end provided with a series of circumferentially spaced intake ports adapted to register with said intake passage, said cylinder extension being provided remote from said closure head with a series of circumferentially spaced exhaust ports adapted to register with said exhaust passage, a piston mounted for reciprocation within said cylindrical extension, a crank shaft, a relatively elongated connecting rod operatively connecting said second piston with one crank of said crank shaft, relatively shorter connecting rods operatively connecting the first mentioned piston with other cranks of said crank shaft, and an intake manifold connecting the first mentioned cylinder with the port of said intake passage, said cylinder provided with a lateral spark plug hole, a spark plug arranged in said hole, and said first mentioned series of ports in said cylinder extension adapted to have one port of said series register with said holes when said cylinder extension has reached the limit of its movement in one direction. 85

15 4. In an internal combustion engine the combination with a two diameter cylinder, provided with ports and a two diameter piston mounted for reciprocation in the cylinder and having the part thereof of smallest diameter provided with ports registering with the ports in the cylinder; of upper and lower chambers provided in the hollow part of said piston, the upper chamber being open at the top of said piston part and being adapted to contain a cooling medium, and being also provided with circumferentially spaced ports to form a fluid break for said cooling medium. 90
